UNITED STATES PATENT OFFICE.

CHARLES H. BOARDMAN, OF COLUMBUS, OHIO.

CRIB.

Application filed October 18, 1924. Serial No. 744,406.

To all whom it may concern:

Be it known that I, CHARLES H. BOARDMAN, a citizen of the United States, residing at Columbus, in the county of Franklin and State of Ohio, have invented new and useful Improvements in Cribs, of which the following is a specification.

The present invention is directed to improvements in children's cribs.

10 The primary object of the invention is to provide a device of this character with a novel form of lock for the drop side thereof, the construction being such that when the side is in its locked position the same will be held firmly against accidental opening, the construction, however, permitting the side to be unlocked or dropped easily and quickly.

20 A further object of the invention is to provide a lock for this purpose so constructed that the mother can upon simply pressing upon a conveniently located handle release the mechanism to unlock the side for dropping, the upward or closing movement of the side causing the lock to automatically operate to lock the side.

With these and other objects in view, this invention resides in the novel features of construction, formation, combination and arrangement of parts to be hereinafter more fully described, claimed and illustrated in the accompanying drawing, in which:—

Figure 1 is a side elevation of the device.

35 Figure 2 is a sectional view on line 2—2 of Figure 1.

Figure 3 is a sectional view on line 3—3 of Figure 1.

40 Figure 4 is a detail view of the locking mechanism.

Figure 5 is a detail view of the one of the plates.

45 Referring to the drawing, 1 designates the end frames, which support the spring frame 2, said spring frame being formed from angle iron. The corner posts 3 of the end frames are provided with longitudinal grooves 4 in which slide the studs 5 carried by the ends of the upper and lower rails 6 and 6' of the side frame 7. The construction thus far described is conventional, and while I deem it desirable to have only one drop side, the construction is such that both sides may drop and be equipped 50 with the locking mechanism.

Suitably fixed to the vertical web 8 of the

side bar of the spring frame 2 are plates 9, said plates being provided with integral right angle plates 10, the upper edges of which being provided with bearings 11. 60 Pivotally engaged in these bearings are the ends of the shaft 12, which terminate in depending arms 13, which in turn terminate in horizontal projections 14, the purpose of which will appear later. Since the plates 9 are arranged in pairs the shaft 12 will be supported in a horizontal position and longitudinally with respect to the side bar of the spring frame, said shaft having a depending arm 12' carried thereby.

Carried by the upper and lower rails 6 and 6' of the side frame are bearings 15 in which is rotatably engaged a rod 16, the upper end of which is provided with a handle 17 for rotating the same. The lower end of the rod terminates in a horizontal arm 18 and extends in an oblique direction under the rail 6', said arm terminating in a horizontal finger 19 which rests against the adjacent arm 12' of the shaft 12, there being a coil spring 20 connecting the rail 6' and the finger 19 to normally hold the same in its inoperative position.

Suitably secured to the lower rail 6' of the side frame is a pair of plates 21, each having a right angle flange 22 formed integral therewith, said flanges having downwardly and inwardly inclined edges 23 which co-operate with the extensions 14 in a manner to be hereinafter described. The lower edges of the flanges are provided with seats 24 adapted to engage the extensions 14 when the side frame is in its elevated or closed position.

When the side frame is in its elevated position the seats 24 are engaged with the extensions 14. To lower the side frame it is only necessary to move the side frame upwardly a short distance to disengage the seats 24 from the extensions 14, whereupon the handle 17 is pressed inwardly to cause the finger 19 to swing the arm 12' with which it contacts inwardly, thus moving the extensions 14 to a position to permit flanges 22 to pass downwardly without interference.

It will be obvious that when the side is moved upwardly that the edges 23 of the flanges 22 will engage the extensions 14 to swing the same inwardly. As soon as the extensions slide from the edges 23 they will swing outwardly so that the seats 24 will

engage therewith when the side frame is released.

What is claimed is:—

1. A crib comprising end frames, a spring frame supported thereby, a shaft pivotally supported upon the spring frame and having extensions upon its ends, a side frame slidably connected with the end frames and having flanges carried thereby, seats formed in the flanges for engaging the extensions to hold the side frame in its elevated position, a rod pivotally supported by the side frame, and means carried by the rod for rocking the shaft to disengage the extensions from the seats.
- 10 2. A crib comprising end frames, a spring

frame associated therewith, a shaft pivotally supported by the spring frame and having extensions upon its ends, a side frame slidably connected with the end frames, a 20 pair of flanges carried by the side frame for slidably engaging the extensions to swing the same inwardly when the side frame is moved upwardly, seats formed in the flanges for engaging the extensions, 25 a finger carried by the side frame for actuating an arm on said shaft to move the extensions from engagement with the seats, and means for actuating the finger.

In testimony whereof I have hereunto 30 set my hand.

CHARLES H. BOARDMAN.
